STOCK FEEDING MECHANISM

Edwin R. Motch, Jr., Shaker Heights, Ohio, assignor to The Motch & Merryweather Machinery Company, Cleveland, Ohio, a corporation of Ohio

Application November 26, 1948, Serial No. 62,135

10 Claims. (Cl. 29—69)

1

This invention relates as indicated to a novel stock feed mechanism and more particularly to a mechanism adapted intermittently to advance a continuous length of stock such as bar stock or tubing to a cold metal sawing machine or like cut-off device.

Metal sawing machines of the type described in Patent No. 2,327,920 to J. G. Moolh, for example, are adapted for automatic operation, and it is of considerable importance that stock feed mechanisms for use in conjunction with such machines likewise be automatic in character and trouble-free in operation. It is often desired to handle rather long lengths of bar stock or the like which must of necessity extend a considerable distance laterally from the machine which is engaged in cutting off sections therefrom. The stock feed mechanism should therefore not require that the stock be inserted therein axially thereof. Accurate gauging of the stock is of prime importance, and it has been common practice to provide an adjustable stop or gauge on the sawing machine to be contacted by the end of the stock and when such stock has been securely clamped, then swung out of the way. Such gauging devices have not always been reliable in operation and also tend to obstruct access to the machine. It is therefore a primary object of my invention to provide stock feed mechanism in which stock gauging means of a very precise and efficient type is included entirely apart from the cut-off or other machine.

It is a further object of my invention to provide such feed mechanism having stock gripping means adapted automatically to accommodate itself to slightly bent stock and the like which might otherwise interfere with smooth operation of the device.

Stock feed mechanisms of known types which repeatedly grip and advance a stock may tend to mar the latter and also are not always entirely reliable in obtaining a firm grip thereon without slippage. It is therefore another object of my invention to provide such mechanism which is adapted to firmly grip the stock adjacent the end thereof, which grip is not released until the same has been consumed.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments

2

of the invention, these being indicative, however, of but a few of the various ways in which the principle of the invention may be employed.

In said annexed drawing:

Fig. 1 is a top plan view of one embodiment of my new stock feed mechanism showing that portion thereof situated adjacent the cut-off or other device to which the stock is to be fed;

Fig. 2 is a similar top plan view which comprises in effect a continuation of Fig. 1;

Fig. 3 is a side elevational view partly in section of the mechanism of Fig. 1;

Fig. 4 is a view constituting a continuation of Fig. 3 and showing that portion thereof shown in plan in Fig. 2;

Fig. 5 is a vertical sectional view taken substantially along the line 5—5 on Fig. 1; and

Fig. 6 is a diagrammatic layout showing the operational relationship between the various parts of the mechanism.

Referring now more particularly to said drawing and especially Figs. 1 through 5 thereof, the embodiment of my invention there illustrated includes an extended trackway comprising a web 1 having upstanding flanges 2 and 3 forming parallel rails along which a carriage or dolly 4 is adapted to travel. Such trackway is supported on uprights 5 and 6, and one end thereof is adapted to abut the cut-off or like machine provided with a work-holding clamp or vise such as a column clamp having a lower jaw 7 and a relatively movable upper jaw 8 (Figs. 3 and 6).

Stock gripping means

35 The stock gripping means of this invention comprises a carriage 4 provided with wheels 9 for reciprocation along rails 2 and 3. At the forward end of such carriage are lower jaw members 10 and 11 dimensioned to correspond in elevation with column clamp lower jaw member 7. An upright post 12 on such carriage supports a swinging arm 13 carrying a vertically adjustable screw 14 in its end. An upright work-gripping jaw 15 adapted to cooperate with

40 lower jaw members 10 and 11 (Fig. 5) in firmly gripping the stock 16 is carried by the lower end of such screw which may be locked in adjusted position by means of hex nuts 17. While such means provides for securing the stock rigidly to carriage 4, there is sufficient play between the flanges of wheels 9 and the sides of the rails to permit such carriage to be turned slightly askew without any jamming or binding should the stock happen to be slightly bent.

45 Mounted in the after end of carriage 4 for

limited lateral movement is a member 18 carrying a clamping device adapted to grip a bar 19 extending longitudinally of the trackway between rails 2 and 3. Such member 18 is retained in place by rod 20, the other end of which is pivotally secured in carriage 4 at 21. The mechanism for gripping bar 19 comprises a cylinder 22 having a piston 23 reciprocable therein to rock arm 24 having an eccentric cam surface 25 adapted to move sliding jaw 26 into clamping engagement with bar 19. A fixed jaw 27 is adapted to bear against the other side of bar 19 in opposition to such jaw 26. Cylinder 22 is of the double-acting type and is therefore provided with two fluid pressure hoses 28 and 29 connecting with opposite ends thereof adapted to lie within sheet metal trough 30 to one side of the trackway. It will be apparent from the foregoing that, in view of the pivotal connection 21, jaws 26 and 27 may clamp bar 19 while at the same time jaws 10, 11 and 15 on the carriage are firmly gripping a slightly bent length of stock without in any way causing binding of the mechanism. An advance roller R serves to steady the carriage when the latter reaches the end of the track.

Auxiliary feed bar reciprocating means

As best shown in Figs. 2, 4 and 5, a hydraulic piston cylinder assembly 31 is provided to effect reciprocation of auxiliary feed bar 19, such assembly being mounted on the underside of track web 1. A rack 32 is connected to the piston of such piston cylinder assembly for reciprocation thereby, an hydraulic shock absorber 33 serving to soften final movement of such piston and rack. Rack 32 drives a pinion 34 which in turn rotates pinion 35 engaging rack 36 secured to the side of auxiliary feed bar 19. Inasmuch as there is provided a 3 to 1 ratio between gear 34 and gear 35, it is obvious that bar 19 and carriage 4 clamped thereto will be reciprocated three times the movement of the piston of piston cylinder assembly 31. A longitudinal rib 37 secured to the other side of bar 19 from such rack 36 is overlaid by hold-down strip 38 which assists in retaining such bar in position. Bar 19 also passes through a guide G and, when retracted, rests upon a supporting roller S rotatable about a horizontal axis.

While there are certain advantages to the employment of hydraulic operating means of the type described, an electric torque motor may instead be provided to drive pinion 35, such motor being of the reversible type and capable of being stalled without danger thereto.

The gauging means

As above indicated, when rack 32 is advanced by piston cylinder assembly 31 to its full extent, bar 19 will move three times such distance. This is therefore the measure of the maximum distance that the stock may be fed by the mechanism illustrated and described herein. It will of course be understood, however, that the ratio between pinions 34 and 35 may be varied to suit any particular need.

By means of the gauging device described below, the distance that the stock is thus fed may be precisely regulated and may be any distance less than the aforesaid maximum.

A gauge rod 39 (Figs. 1 and 2) is journalled for axial reciprocation in end support 40 and pillow block 41. A collar 42 is pinned thereto closely adjacent but slightly spaced from such

end support 40. A similar collar 43 is adjustably secured to rod 39 adjacent pillow block 41 (Fig. 2) and is connected with a sliding stop 44 by means of a micrometer adjusting screw 45.

5 A sleeve 46 slidable along rod 39 is secured to bar 19 adjacent the left-hand end of the latter (Fig. 1). When such sleeve engages collar 42 during the feeding reciprocation toward the cut-off or other machine, it moves rod 39 slightly to the left, although not sufficiently so to cause collar 42 to engage end support 40. Movement of bar 19 to the left is actually halted by engagement of the end of such bar with stop 47 which carries end support 40. In so doing, bar 19 depresses plunger 48 to operate micro-switch 49 for a purpose explained below.

When auxiliary feed bar 19 is reciprocated in the other direction (to the right) such sleeve 46 carried thereby will engage stop 44 to shift rod 39 to the right, such latter movement however being slight and only sufficient to cause operation of micro-switch 50 and without engagement between collar 43 and pillow block 41. A shock absorber 51 connected to the right-hand end of rod 39 softens the impact and limits movement of rod 39 and therefore bar 19 to the right.

General operation

The general operation of my new feed mechanism may now be readily understood. A length of stock 16 will be placed upon the feeder laterally with its right-hand end, as viewed in Fig. 3, securely clamped by jaws 10, 11, and 15 on carriage 4. The other end of the stock will rest on lower jaw 7 of the column clamp 52. The gauge will be set for the proper cut by securing collar 43 in approximately the correct position thereon and adjusting stop 44 by means of micrometer screw 45 (as shown in Figs. 2 and 3) such gauge is set for the maximum length of cut, i. e. maximum reciprocation of auxiliary feed bar 19. Before starting automatic operation of the mechanism, column clamp 52 will be manually operated to clamp the stock during a preliminary cropping cut.

With such column clamp clamped (Fig. 6) pressure will build up in fluid pressure line 53 leading to the lower end of cylinder 54, in which piston 55 reciprocates to operate lever arm 56. Fluid pressure is supplied by pump 57 from sump 58 to main pressure line 59 provided with a relief valve 60. Return (exhaust) lines are shown in dash line on Fig. 6. As such pressure builds up in line 53 it overbalances pressure sequence valve 61 and passes through four-way valve 62 to admit pressure to line 63 and the right-hand end of cylinder 64, thereby advancing piston 65 and the saw carriage or other cut-off tool.

Movement of such piston and carriage operates micro-switch 66 to shift four-way valve 67 to admit fluid pressure from line 68 to line 69 leading to cylinder 22 on carriage 4. (Pressure sequence valve 70 has, of course, already been overbalanced to admit pressure to line 68.) Piston 23 is thereby reciprocated to release auxiliary feed bar 19. Operation of switch 66 also causes double solenoid operated four-way valve 71 to be shifted to admit fluid pressure to line 72 and thereby cause piston-cylinder assembly 31 to reciprocate rack 32 to shift auxiliary feed bar 19 to the left as viewed in Fig. 6. Carriage 4 remains stationary since it is no longer clamped to bar 19 but is clamped to stock 16 likewise held in column clamp 52. 73 and 74 are speed control valves and 75 is a pressure reducing valve.

Arm 46 on bar 19 (Figs. 1, 2, and 6) strikes stop 44 and moves gauge rod 39 sufficiently against shock absorber 51 to operate microswitch 50. Operation of switch 50 shifts valve 67 to cause carriage 4 to again be clamped to bar 19.

After completion of the cut, limit switch 77 is operated to shift valve 62 to admit pressure to line 78 and to connect line 63 to exhaust, thereby retracting piston 65 and returning the saw carriage. 79 is a volume control regulator for regulating the speed of advance of piston 65 while permitting rapid retraction of the latter.

When piston 65 is fully returned, switch 66 is again operated to shift valve 80 to admit pressure to line 81, thereby unclamping column clamp 52. As upper jaw 8 rises, switch 82 is operated to shift valve 71 to admit pressure to line 76 and connect line 72 to exhaust. Piston-cylinder assembly 31 thereupon advances bar 19 together with carriage 4 and stock 16 until arm 46 engages collar stop 42 on gauge rod 39. Bar 19 continues its movement slightly, moving rod 39 therewith and thereby releasing switch 50, until its end strikes stop 47 and switch 49 is operated. Operation of switch 49 shifts valve 62 to again connect line 63 to pressure and to shift valve 80 to connect line 53 to pressure. As previously explained, however, no pressure will reach line 63 until the stock has been firmly clamped by the column clamp 52 and pressure-sequence valve 61 overbalanced. The cycle has thus been completed.

As previously indicated, the present invention is not concerned with the particular operation of the machine to which the stock is fed, the above example being for illustration only. It is only necessary that clamping means such as column clamp 52 be provided for cooperation with the feed mechanism proper.

All feeding and gauging mechanism is removed from the work station where it will offer no obstruction. It is positive and automatic in operation and incapable of damaging either the stock or the machine.

Other modes of applying the principle of the invention may be employed, change being made as regards the details described, provided the features stated in any of the following claims or the equivalent of such be employed.

I therefore particularly point out and distinctly claim as my invention:

1. A device for intermittently advancing a work piece comprising a guide-way, work gripping means mounted for movement along said guide-way and adapted to be turned somewhat askew thereof, a fixed clamp operative rigidly to hold such work against movement, a member reciprocable longitudinally of said guide-way, and means on said work gripping means operative to engage said reciprocable member for movement of said work gripping means therewith, said member engaging means being pivotally secured to said work gripping means to permit the latter to turn somewhat askew when gripping a bent work piece or the like.

2. A device for intermittently advancing an elongated work piece comprising a straight track, a carriage on said track adapted to travel therealong and to be turned somewhat askew thereof, means on said carriage adapted throughout the entire operation to grip an elongated work piece disposed longitudinally of said track, fixed work clamping means at one end of said track, an elongated member reciprocable longitudinally of said track, and clamping means pivotally mounted

on said carriage adapted to clamp said reciprocable member for movement of said carriage therewith.

3. A device for intermittently advancing an elongated work piece comprising a straight track, a carriage on said track adapted to travel therealong and to be turned somewhat askew thereof, means on said carriage adapted throughout the entire operation to grip an elongated work piece disposed longitudinally of said track, fixed work clamping means at one end of said track, an elongated bar reciprocable longitudinally of said track, and fluid-pressure actuated clamping means carried by said carriage in pivotal relationship to said work gripping means on said carriage and adapted to clamp said reciprocable bar for movement of said carriage therewith.

4. A device for intermittently advancing an elongated work piece comprising a straight track, a carriage on said track and adapted to travel therealong, means on said carriage adapted throughout the entire operation to grip an elongated work piece disposed longitudinally of said track, fixed work clamping means at one end of said track, a rigid elongated bar reciprocable longitudinally of said track, fluid-pressure actuated clamping means carried by said carriage in pivotal relationship to said work gripping means on said carriage and adapted to clamp said reciprocable bar for movement of said carriage therewith, a rack on said bar, a fluid pressure actuated piston-cylinder assembly, a second rack constituting an extension of such piston, pinion means interconnecting said racks for reciprocation of said bar, and gauging means limiting reciprocation of said bar comprising a rod mounted parallel thereto, fixed means limiting forward movement of said bar, an arm on said bar, a sleeve carried by said arm and movable along said rod, and an adjustable stop on said rod adapted to engage said sleeve and thereby to limit return movement of said bar.

5. A device for intermittently advancing a work piece comprising a guide-way, work gripping means mounted for movement along said guide-way operative continuously tightly to grip such work throughout the entire work advancing operation, a fixed clamp operative to hold such work rigidly against movement, a member reciprocable longitudinally of said guide-way, means adapted releasably to secure said work gripping means to said reciprocable member for movement therewith, a fixed stop limiting forward movement of said reciprocable member, a rod mounted parallel to said member, a movable stop adapted to be secured in adjusted position along said rod, a projection on said reciprocable member between said fixed stop and said adjustable stop adapted to engage the latter to limit return movement of said member, and drive means operative to reciprocate said member to the extent permitted by said stops.

6. A device for intermittently advancing an elongated work piece comprising a straight track, a carriage on said track and adapted to travel therealong, means on said carriage adapted throughout the entire operation to grip an elongated work piece disposed longitudinally of said track, fixed work clamping means at one end of said track, a rigid elongated bar reciprocable longitudinally of said track, a fixed stop limiting forward movement of said reciprocable bar, a rod mounted parallel to said bar for longitudinal reciprocation, means limiting reciprocation of said rod in a rearward direction, a movable stop adapted to be secured in adjusted position along

said rod, a projection on said bar between said fixed stop limiting forward movement of said bar and said adjustable stop on said rod adapted to engage the latter to shift said rod to the extent permitted by said limiting means, clamping means on said carriage operative to clamp said bar for reciprocation of said carriage therewith, a switch operable by movement of said rod rearwardly to activate said last-named clamping means to clamp said bar, means operative to activate said last-named clamping means to release said bar after said bar has advanced the full distance permitted by said fixed stop and said fixed work clamping means has clamped the work, and drive means operative to reciprocate said bar to the extent permitted by said stops.

7. A device for intermittently advancing an elongated work-piece comprising a straight track, a carriage on said track adapted to travel therealong, means on said carriage adapted through-out the entire operation to grip an elongated work-piece disposed longitudinally of said track, fixed work clamping means at one end of said track, a rigid elongated bar reciprocable longitudinally of said track, fluid-pressure actuated clamping means carried by said carriage adapted to clamp said reciprocable bar for movement of said carriage therewith, a fluid pressure actuated piston-cylinder assembly operatively connected with said bar and adapted to reciprocate the same, and gauging means limiting reciprocation of said bar comprising a rod mounted substantially parallel thereto, fixed means limiting forward movement of said bar, a projection on said bar movable along said rod when said bar is thus reciprocated, and an adjustable stop on said rod adapted to engage such projection on said bar and thereby to limit return movement of said bar.

8. A device for intermittently advancing an elongated work-piece comprising a straight track, a carriage on said track adapted to travel therealong, means on said carriage adapted through-out the entire operation to grip an elongated work-piece disposed longitudinally of said track, fixed work clamping means at one end of said track, a rigid elongated bar reciprocable longitudinally of said track, means operative directly to interconnect said bar and carriage during forward movement of said bar, for movement of said carriage therewith, and to disconnect said bar and carriage during return movement of said bar, a fluid pressure actuated piston-cylinder assembly operatively connected with said bar and adapted to reciprocate the same, adjustable stop means limiting return movement of said bar, fixed stop means limiting forward movement of said bar, and stallable drive means operative alternatively to urge said bar against said fixed and adjustable stops.

9. In mechanism for intermittently advancing an elongated length of stock to a cut-off or other machine, a stationary clamp adapted to clamp such stock during the performance of an opera-

tion thereon by such machine, and means operative to feed such stock through said clamp when the latter is relaxed comprising an elongated member reciprocable toward and away from said clamp, means operative to interconnect said member and stock during forward movement of said member toward said clamp, for movement of such stock therewith; and to disconnect said member and stock during return movement of said member away from said clamp, a fixed stop limiting forward movement of said member, a rod mounted parallel to said member, a movable stop adapted to be secured in adjusted position along said rod, a projection on said member adapted to engage said adjustable stop to limit return movement of said member, and drive means operative to reciprocate said member to the extent permitted by said stops.

10. In mechanism for intermittently advancing an elongated length of stock to a cut-off or other machine, a stationary clamp adapted to clamp such stock during the performance of an operation thereon by such machine, and means operative to feed such stock through said clamp when the latter is relaxed comprising a rigid elongated bar reciprocable toward and away from said clamp, a fixed stop limiting forward movement of said reciprocable bar toward said clamp, a rod mounted parallel to said bar for longitudinal reciprocation, means limiting reciprocation of said rod in a rearward direction away from said clamp, a movable stop adapted to be secured in adjusted position along said rod, an arm on said bar, a sleeve carried by said arm and movable along said rod between said fixed stop and said adjustable stop adapted to engage the latter to shift said rod to the extent permitted by said means limiting reciprocation thereof, clamping means operative to interconnect said bar and stock during forward movement of said bar, for movement of such stock therewith, and to disconnect said bar and stock during return movement of said bar, a switch operable by return movement of said rod to activate said last named clamping means to interconnect said bar and stock, means operative to activate said last named clamping means to disconnect said bar and stock after said bar has advanced the full distance permitted by said fixed stop and said stationary clamp has clamped the work, and drive means operative to reciprocate said bar to the extent permitted by said stops.
